UNITED STATES PATENT OFFICE

2,366,573

AUTOMATIC RADIO TUNER

Joseph L. Swallow, Lombard, Ill., assignor to
Wells-Gardner & Co., Chicago, Ill., a corpora-
tion of Illinois

Application July 16, 1942, Serial No. 451,128

7 Claims. (Cl. 250—20)

The tuning device of the present invention is designed primarily for use in situations wherein it is desirable to pick up reports or signals in recurrent sequence from a group of stations transmitting upon different frequencies, and in order to successively bring in these stations provision is made for automatically adjusting the movable plates of the condenser in each case, and for a stated interval, to the required position to bring in the stations in sequential order.

In the present mechanism it is preferred to employ a constantly and uniformly rotating cam carrying disk or plate having mounted thereon a group of individually adjustable cam members which afford a rolling contact for the member which oscillates the shaft carrying the condenser plates, and since the present mechanism must be capable of continuous and uninterrupted operations over long periods of time it is highly important that the adjustable cam surface shall be of such character as to afford a smooth and sinusous track uninterrupted by projections or sharp variations in contour which might be subject to wear or excessive friction, and the adjustable cam assembly of the present invention has been designed to meet these requirements and at the same time permit easy and accurate adjustments of the individual cam members.

A further important object of the present invention is to provide adjustable means for timing the intervals of movement and rest of the adjustable cam carrying plate so that each of the sending stations will remain tuned in for a predetermined interval, as for instance ten seconds, after which a quick shift will bring the next station of the series into tune. By suitable manual adjustment, the mechanism can be set for a number of different periods of reception, as for instance three seconds, four seconds, five seconds, etc., up to ten seconds, for reception, with a short intervening interval, as for instance one second, for the readjustment of the condenser.

Provision is also made for disconnecting the automatic adjustment mechanism so that the condensers may be adjusted by manual operation in the usual manner.

The invention also relates to the power transmission trains employed and to the means provided for housing and enclosing the operating mechanism within a casing adapted to contain oil for lubricating purposes.

Further objects and details will appear from the description of the invention in conjunction with the accompanying drawings, wherein:

Figure 1 is a perspective view of the entire

mechanism showing the adjustable cam assembly at the right and the condenser groups at the left;

Fig. 2 is a perspective view with the casing partly broken away to reveal the interior transmission mechanism;

Fig. 3 is a face view of the frequency cam assembly and mountings therefor, with the clamping plates partly broken away;

Fig. 4 is a detail in plan of the rotatable disk or turntable for carrying a group of timing cams;

Fig. 5 is a longitudinal sectional detail taken on line 5—5 of Fig. 3, showing the stem and adjusting screw for one of the frequency cam members;

Fig. 6 is a perspective view of one of the frequency cam members;

Fig. 7 is a view showing the frequency cam carrying disk plate removed to expose the connections for displacing the associated parts to permit substitution of another disk plate;

Fig. 8 is a similar view showing the associated parts displaced;

Fig. 9 is a rear face view of the frequency cam carrying plate showing the mounting for the same;

Fig. 10 is a perspective view of the spur-gear for driving the frequency cam carrying disk plate; and

Fig. 11 is a perspective detail of the coupling for permitting disengagement of the automatic drive mechanism from the condenser shaft to allow for manual adjustment of the condenser.

The automatic adjusting mechanism of the present invention is enclosed within a box-like housing of rectangular stepped formation comprising front and rear side walls 10 and 11, upper and lower inner end walls 12 and 13 standing in stepped arrangement, an outer end wall 14 of full height, an upper cover wall 15, a lower cover wall 16, and a base partition plate 17 which elevates the working mechanism above the floor of the housing, thus affording an oil reservoir in the base of the housing.

Within the interior of the casing is located a frame which includes a cross partition plate 18 spaced from the outer end wall 14, inner and outer longitudinally extending plates 19 and 19a, and a shelf 20 which connects along its edges with the plates 18 and 19, and forms in conjunction therewith an interior mounting for certain of the operating mechanisms presently to be described. The frame also includes an end plate 18a in spaced relation to the plate 18, and in abutment with the wall 14, the various portions of the frame being rigidly united together. The

lower cover wall 16 affords a mounting for a motor 21 which affords power for the enclosed mechanism which is driven through a suitable gear reduction assembly mounted within a gear box 22.

On the exterior of the machine, and immediately adjacent the front end wall 14, is located the frequency cam assembly 23, which is removably mounted upon the outer end of a fixed journal shaft 24 which extends through the front end wall and has its inner end mounted within the partition plate 18. The cam assembly is held in place by a thumb nut 25 on the end of the shaft, which may be removed to permit other cam assemblies having different spacing arrangements to be substituted as occasion may require.

The cam assembly comprises a disk shaped base plate 26 having fixedly and concentrically mounted thereon a plurality of segments 27 of a lesser radius than the base plate and spaced from one another to afford radial grooves or channels 28, which converge inwardly to a collar 29 which is provided with a plurality of notches 30 in its outer edge. The collar stands in spaced relation to an enlarged head 31 on the end of the shaft 24, as will appear from an inspection of Fig. 9.

The base plate 26 stands in adjacent relation to a stepped disk 31a which is freely mounted on the shaft head 31 and is cut through save at its rim by opposite radially extending slots 31b which are narrowed at their inner ends to clamp the ends of oppositely extending leaf springs 31c whose free outer ends are free to have limited movement within the surrounding slots. The ends of the leaf springs are looped to receive the ends of pins 31d projecting from the face of the base plate. The stepped disk 31a has screwed thereto a spur-gear 53 which forms part of the transmission train which drives the cam assembly but the spring connection with the base plate permits the latter to be exactly centered by the detent mechanism presently to be described.

Each of the radial channels 28 affords a guideway for a cam carrying stem 32 which, as shown in Fig. 5, is provided with a smooth outer bore 33 merging at its inner end into a threaded bore 34 which receives the threaded end of an adjusting screw 35, provided at its inner end with a head 36 and at its outer end with a cross notch 37 adapted to receive a small screw driver.

The stem at its outer end is provided with an inwardly extending ear 38 which is rounded on its outer face to afford an easy riding surface, which ear merges into the rim of a head plate 39 inwardly projecting from the inner face of the stem. The outer edges of the head plate are rounded to merge into the curvature of the ear, so that the entire acting surface of these parts will afford an easy curvature or riding contact for the mechanism presently to be described.

At one end of the head plate 39 is mounted an arcuate cam bar 40 bifurcated at its inner end 41 to straddle the edge of the head plate upon which it is pivoted by a pintle 42. The free end 43 of the cam bar is of reduced thickness and offset inwardly with respect to the longitudinal center of its pivoted inner end, so that its outer face will substantially align with the inner face of the head plate 39. The opposite end of the head plate carries a grooved stud 44 which is positioned to receive the free end of the next adjacent cam bar which, during the adjustment of the parts, may slip freely within the groove in the stud as indicated in the different setting of the cam bars, as shown in Fig. 3.

The cams are adapted to be variably adjusted by turning the respective screws 35 to bring the outer ends of the stems with the rounded head plates and cams each to the desired positions to secure the proper tuning for each of the stations, and after the various adjustments have been made the parts are locked in position by means of clamping segments 45, which are held in clamping position by means of screws 46, which are preferably located in close relation to the respective cam stems, so that when screwed down they will hold the respective cams tightly in relatively adjusted position.

The cam assembly heretofore described is positioned to impart the intended degrees of movement to a roller 47, which is positioned to ride upon the respective cam bars as the cam assembly is intermittently rotated from one position to the next, during the cycle of operations required in bringing each of the stations in turn into tune for a predetermined period of time, the mechanism being actuated in such a way as to impart a relatively quick adjusting movement, during which the contacting cam bar will afford an easy riding surface for the roller until the head of the next succeeding cam moves to a position beneath the roller, at which point the movement is arrested for a predetermined period, with the roller standing in such position as to tune in the particular station whose frequency corresponds to the adjustment of the cam head currently in operating position.

In order that each cam head in turn will be exactly centered during the corresponding tuning period, the edge of the base plate 26 is provided with a series of notches 46a, one opposite each cam head, which notches in turn coat with a detent 46b (see Figs. 7, 8) carried at the end of a pivoted arm 46c drawn inwardly by a spring 46d and since the base plate 26 is permitted to have limited rotation independently of the hub upon which it is mounted, and of the mechanical driving mechanism which rotates it by stages from one position to the next, the detent will act at each stage to impart the final centering movement to the base plate which is of major importance in securing accurate tuning.

The movements imparted to the cam roller 47 are reflected in the angular adjustment imparted to the outer section 48 of a divided shaft, which also includes an inner section 49 adapted to be clutched to the outer section through the medium of a manually operated clutch 50 (see Fig. 11), actuated by a knob 51 within convenient reach of the operator. With the shaft sections clutched together for automatic operation, the angular rotary movements of the shaft will impart the desired adjustment to gangs of condenser plates 52 which are carried by the inner shaft section, and operate in the usual manner to tune in stations of different frequencies.

As shown in Fig. 11 the outer shaft section 48 mounts a spring backed sleeve 48a which is slotted to receive a fin 48b outwardly extending from the shaft so that the parts will rotate in unison while permitting sliding adjustment of the sleeve which is effected by rotation of the knob 51 at the outer end of the transverse shaft 51a which at its inner end carries a finger 51b bearing against the face of a flange ring 51c at the outer end of the sleeve 48a and which is backed by a spring 51d abutting against a collar 51e pinned to the shaft section 48. The sleeve at its inner end carries an arm 51f provided with a finger 51g which when the shaft sections are in

clutch freely enters a notch 49a in a clutch head 50a, being held snugly against the face of the notch which receives the driving thrust by the upper finger of a bell crank 50b, the lower finger of which is drawn back by a spring 50c. This arrangement permits the finger 51g to slip freely into or out of the notch 49a when the parts are being clutched or unclutched, but maintains close driving contact when the shaft is being rotated.

The clutch head 50a is fast on the inner shaft section which connects with the condenser, but to ensure instant automatic setting of the condenser shaft after manual operation, the clutch head is provided with a threated cam face 50d which when the sleeve 48a is free to move under the thrust of the spring 51d will force the rounded end of the finger 51g against the threated cam face and cam the condenser shaft section around until it comes into correct register with the position imparted to the shaft section 48 by the currently active cam head on the base plate 26 at which point the finger will slip into the notch 49a in the clutch head and hold the parts in register as automatic operation is resumed.

The means provided for intermittently timing the rotation of the cam assembly will now be described: As before stated, the cam assembly is freely mounted upon the fixed journal shaft 24, and the hub 31 carries a removable spur-gear 53. The spur-gear is adapted to mesh with a transmission spur-gear 54 carried by a bell crank 55 and in mesh with a spur-gear 56 carried by a Geneva movement shaft 57 which is journalled at its outer end through the frame plate 18a and the end wall 14 and at its inner end within the partition plate 18.

The shaft 57 carries a star wheel 58 of the conventional type provided with slots 59 in its edge, which are adapted to be engaged by a pin 60 on an arm 61 extending outwardly from a generally cylindrical body block 62 provided with a slot 63. The curvature of the body block conforms to the concave curvature of the edges of the star wheel intermediate the slots 59, and the block is carried by a sleeve 64 which is slidably mounted upon a shaft 65 carrying a coil spring 66 which bears against the block and normally forces the block and associated parts inwardly into such position that the pin 60 will clear the star wheel without imparting rotation thereto.

In order to bring the pin 60 into coaxing relation with the star wheel, a grooved collar 67 is carried by the sleeve 64 which engages the outer free end of an arm 68 carried by a tubular stem 69 which is pivoted between ears 70 by means of a pivot pin 71. The tubular stem 69 carries a lower arm 72 from which depends a pin 73 carrying a roller 74 so disposed that, as the roller is moved inwardly by a selected member of a group of timing cams 75, an outward thrust will be imparted to the sleeve 64 and the block 62, thereby bringing the pin 60 into position to engage with one of the slots in the star wheel.

The grooved collar 67 has extending therefrom a slotted coupling sleeve 76 which coacts with a pin 77 outwardly extending from the shaft 65, so that the coupling with the grooved collar and block 62 will be rotated by the shaft irrespective of the adjustment of the parts thereon. Rotation is imparted to the shaft through the gear reduction train in the gear box 22, through a ratchet faced coupling 65a so that driving rotation is imparted in one direction only.

In order to effect desired ratios in the periods of rotation and rest of the cam assembly, manu-

ally operated adjusting means are provided which will now be described. Each of the cams 75 is properly configured to secure a desired ratio of rest and motion conformable to a predetermined scheme of operations. Thus it is possible to set the mechanism to secure reception from each of the stations for a period of three seconds, four seconds, or any period up to ten seconds, with intervals of one second between each reception period to allow for the required adjustment. Each of the cams 75 thus has one or more high points or humps 78 which, when the particular cam is brought into proximity with the roller 74, will engage and move back the roller to effect a momentary engagement of the pin 60 with one of the star wheel slots 59 to impart a single step of movement to the cam assembly, after which the pin will be disengaged and restored to idle position by the spring 66. The cam assembly will then stand motionless until the operation is repeated, during which the condenser plates will stand in the proper position to afford reception at the desired frequency. Certain of the cams 75 may be provided with two or more humps or projections which will vary the periods of reception in conformity with any desired ratio.

All of the cams 75 are journalled upon a carrier plate 79, and each of the cams has connected therewith a spur pinion 80, all of the pinions being in mesh with a master pinion 81 (Fig. 4). The carrier plate is provided in its center with a tubular adjusting shaft 82 carrying a bevel pinion 83 at its upper end, which pinion meshes with a bevel pinion 84 on the inner end of a horizontal shaft 85 carrying a knob 86 at its outer end, with an adjacent pointer 87 to indicate the adjustment required. The rotation of the knob serves to impart rotation to the carrier plate to bring the desired cam 75 into coaxing relation with the roller 74 in order to secure radio reception for the desired periods of time.

Constant rotation is imparted to each cam 75 of the entire series through the master pinion 81, which is driven by an inner vertical shaft 90, which passes upwardly through the tubular shaft 82 and is provided with a worm wheel 91 on its upper end which engages with a worm 92 on a shaft 93. The latter shaft carries a spur pinion 94 which meshes with a spur pinion 95 splined onto the shaft 65, which is driven at a constant rate by the motor 21 which is preferably a synchronous motor. Accurate centering of the carrier plate 79 is ensured by the provision of notches 95a in the rim of the plate which coax with a suitable spring detent not shown.

In order to disengage the automatic tuning mechanism, the shaft 51a which carries the knob 51 is provided with an arm 97 pivoted to the end of a rod, not shown, which actuates suitable clutch mechanism 98, which need not be described in detail, but which serves, when the automatic drive is disengaged, to clutch in a gear train 100, which permits the dial 101 to be operated by a manually controlled knob 102 in the usual manner, it being understood that when the cam assembly is in clutch, the dial will likewise be rotated to afford a visual record displaying the frequency of the station which is tuned in for the time being.

It will be understood that the tuning frequency cam assembly is made removable, so that another one of several cam assemblies may be substituted therefor in order to accommodate different numbers of stations to the receiving or central station; and it will likewise be understood

that the individual frequency cams may be so adjusted as to bring in the same station two or more times during a single cycle of rotation.

In removing and replacing the cam assemblies it is necessary to temporarily displace certain of the mechanisms which coact with the cam assemblies and the devices employed for this purpose are illustrated in Figs. 7 and 8. It will there be seen that the gears 54 and 56, the detent 46 and the roller 47 must be moved back out of normal operating position shown in Fig. 7 to the clearing position shown in Fig. 8, so that they will not interfere with the easy and convenient manipulations required in making the substitution.

To this end I provide a slide bar 103 having a pin and slot connection 104 with the wall 14 of the housing. The slide bar carries three depending fingers 105, 106 and 107, and the slide bar is moved by a lever 108 pivoted by a pin and slot 109 to the end of the bar and fulcrumed at 110. The lower end of the lever carries a segment 111 provided on its inner edge with a notch 112 below which the face 113 of the segment is beveled outwardly and is positioned to engage a roller 114 on the inner face of a disk 115 carried by a stud shaft 116 (Figs. 2, 10) entered through the end wall of the housing and provided with a bolt head 117 adapted to receive a wrench. The bolt shaft carries a spur-gear 118 having a slotted hub 119 which receives a pin 120 projecting outwardly from the shaft and the parts are so disposed that when the bolt shaft is turned in a clockwise direction (Fig. 7) it will finally engage the lower ends of the lever 108 and swing the same outwardly until the roller reaches the notch 112 and this will impart an inward swing to the upper end of the lever and a sliding movement to the bar 103 moving the parts to the position shown in Fig. 8.

During this movement the finger 105 will engage the upper end of the bell crank 55; the finger 106 will engage the detent arm 46; and the finger 107 will engage a pin 121 on the pivoted arm carrying the roller 47 so that the gears, the detent and the roller will be moved back in unison to the position shown in Fig. 8 against the weight of the roller, and the tension of springs 46a and 122, which is connected with bell crank 55.

This permits the entire cam assembly, including the stepped disk and spring connection carried thereby, as well as the spur-gear 53 to be removed as a unit by the mere removal of the thumb nut 25 on the end of the shaft 24. The spur-gear 118 meshes with a gear 123 on the shaft 65 so that during the clearing cycle of movements the shaft and parts carried thereby will partake of the movement but at the end of the cycle will be restored to their original position, so that the timing order of the mechanism will not be disturbed by the substitution of a new frequency cam assembly.

In order to indicate which of the stations is tuned in for the time being an electric bulb (not shown) is provided for each station at a point visible to the operator, and the base plate 26 on its inner face is provided with a series of movable contacts 124 arranged in spiral relation and individually located to register with a corresponding series of fixed contacts 125 (Fig. 7) adjacent the face of the plate so that as the cams are intermittently moved to tuning position the corresponding contacts will be brought into register and the identifying bulb which is in circuit

with the registering contacts will be illuminated during the period of reception.

In practical use it is customary to supply five tuning frequency cam assemblies having respectively 6, 7, 8, 9 and 10 cam groups corresponding to station groups consisting of 6, 7, 8, 9 and 10 stations respectively. Where five stations or less are comprised within the group, certain of the above cams can be used when the number of individual cams is equally divisible by the number of stations desired. For example, where a two station set-up is desired, the cam assembly having six individual cams would be chosen, as it carries the smallest number of cams divisible by 2.

It will, of course, be understood that the timing cams 75 are individually configured to throw the pin 60 into the star wheel slot at the properly timed instant to impart a shift in the cam assembly, and that each cam is also designed to afford a predetermined period of rest for radio reception conformable to the positions indicated for the adjustments of the knob 86.

Operation

In the preliminary adjusting of the several tuning cams it will be desirable to tune each of the stations, in by hand until clear reception is attained, and thereupon adjust the corresponding cam stem to the proper position to contact the roller 47 carried by the arm on the shaft section 48. When proper adjustment is effected, the adjacent clamping screw 48 will be turned down to lock the cam in position, and thereafter the next cam will be similarly adjusted and locked until all of the cams have been set to the required positions to tune in the respective stations in the proper sequence.

After the required setting of the tuning cams 40 has been made, the desired timing cam will be turned into position to engage the roller 47 at the required instant, and if power is now applied to the gear train, the mechanism will operate to bring each station into tune for the required 45 period and in the desired sequence. It will be understood that all of the timing cams will be rotated constantly by the master pinion, but that only one of these cams will function to engage the roller 47.

When the hump on the selected cam engages the roller 77, the pin 60 will move into position to engage the star wheel and impart a momentary quarter movement thereto sufficient to quickly turn the tuning cam assembly to the next position of adjustment, at which time the pin will disengage from the star wheel, and the radio reception will continue for the intended interval, depending upon the configuration of the timing cam in immediate service.

The tuning cam mechanism is designed to afford means for easy and accurate adjustment, and at the same time to maintain a smooth contact surface of sinuous or undulating character at all times and without any abrupt variations or obstructions which would tend to cause wear in an instrument which is designed for continuous operation through long periods of time. By the use of a synchronous motor, accurate timing will be maintained in conformity with the setting of the mechanisms, so that tuning to each station at the intended instant will be effected.

I claim:

1. In an automatic radio tuner, the combination of a condenser including a group of adjustable plates adapted to establish selective tuning

with the members of a group of stations operating on different wave lengths, power transmission connections for adjusting the plates and adapted to be variably moved, a movable carrier located in proximity to the terminus of said connections distant from the condenser, a group of cam elements mounted upon the carrier, each adjustable with relation to the terminus of the connections, a member carried by the connections positioned to be successively engaged by each of the cam elements for imparting movements thereto corresponding in degree to the adjustments of the cam elements, means for imparting adjusting movements to the carrier to bring the cam elements successively into coacting relation alternating with periods of rest to permit radio reception, each of the cam elements consisting of a stem adjustable on the carrier, and a cam bar pivoted at its inner end to the outer end of its stem and having its free end slidably supported upon the outer end of the next adjacent stem to afford a continuous undulatory trackway for the contact of the member carried by the power connections irrespective of the adjustments of the individual cam stems.

2. In an automatic radio tuner, the combination of a condenser including a group of adjustable plates adapted to establish selective tuning with the members of a group of stations operating on different wave lengths, power transmission connections for adjusting the plates and adapted to be variably moved, a rotatable carrier located in proximity to the terminus of said connections distant from the condenser, a group of cam elements mounted upon the carrier, each adjustable with relation to the terminus of the connections, a member carried by the connections positioned to be successively engaged by each of the cam elements for imparting movements thereto corresponding in degree to the adjustments of the cam elements, means for imparting adjusting movements of rotation to the carrier to bring the cam elements successively into coaxing relation alternating with periods of rest to permit radio reception, each of the cam elements consisting of a stem adjustable radially on the carrier, and a cam bar pivoted at its inner end to the outer end of its stem and having its free end slidably supported upon the outer end of the next adjacent stem to afford a continuous undulatory trackway for the contact of the member carried by the power connections irrespective of the adjustment of the individual cam stems.

3. In an automatic radio tuner, the combination of a condenser including a group of adjustable plates adapted to establish selective tuning with the members of a group of stations operating on different wave lengths, power transmission connections for adjusting the plates and adapted to be variably moved, a movable carrier located in proximity to the terminus of said connections distant from the condenser, a group of cam elements mounted upon the carrier, each adjustable with relation to the terminus of the connections, a member carried by the connections positioned to be successively engaged by each of the cam elements for imparting movements thereto corresponding in degree to the adjustments of the cam elements, means for imparting adjusting movements to the carrier to bring the cam elements successively into coacting relation alternating with periods of rest to permit radio reception, means for variably timing the periods of movement and rest of said carrier moving means, said means including an adjustable

mounting carrying a group of differently configured cams, means for rotating all of the cams in unison, and manually operable connections to bring any selected cam of the group into coaxing relation with the carrier moving means.

5 relation with the carrier moving means.

4. In an automatic radio tuner, the combination of a condenser including a group of adjustable plates adapted to establish selective tuning with the members of a group of stations operating on different wave lengths, power transmission connections for adjusting the plates and adapted to be variably moved, a movable carrier located in proximity to the terminus of said connections distant from the condenser, a group of cam elements mounted upon the carrier, each adjustable with relation to the terminus of the connections, a member carried by the connections positioned to be successively engaged by each of the cam elements for imparting movements thereto corresponding in degree to the adjustments of the cam elements, means for imparting adjusting movements to the carrier to bring the cam elements successively into coaxing relation alternating with periods of rest to permit radio reception, means for variably timing the periods of movement and rest of said carrier moving means, said means including a turntable mounting thereon a group of differently configured cams, means for rotating all of the cams in unison, and manually operable connections to bring any selected cam of the group into coaxing relation with the carrier moving means, and the carrier moving means including a star wheel in train with the carrier, a constantly rotating member adapted to be moved to position to engage and actuate the star wheel, and connections positioned to be contacted by the coaxing cam for moving the rotating member into momentary engagement with the star wheel to effect readjustment of the carrier.

40 5. In an automatic radio tuner, the combination of a condenser including a movable element adapted to establish selective tuning with the members of a group of stations operating on different wave lengths, a rotatable power transmission connection with said movable condenser element adapted to be variably rotated and terminating in an eccentrically mounted roller, a group of individually adjustable cam members each adapted in turn to engage and move said roller 45 50 in an amount corresponding with the setting of each of said adjustable members, a rotatable carrier for the group of adjustable members, means including gearing and a Geneva movement for rotating said carrier to bring said adjustable members successively into coacting relation with said roller, and an adjustable member adapted 55 when moved to displace said roller and said gearing to permit convenient removal of said carrier.

6. In an automatic radio tuner, the combination of a condenser including a movable element adapted to establish selective tuning with the members of a group of stations operating on different wave lengths, a rotatable power transmission connection with said movable condenser element adapted to be variably rotated and terminating in an eccentrically mounted roller, a group of individually adjustable cam members each adapted in turn to engage and move said roller in an amount corresponding with the setting of each of said adjustable members, a rotatable carrier for the group of adjustable members, means including gearing and a Geneva movement for rotating said carrier to bring said adjustable members successively into coacting relation with said roller, an adjustable member adapted when moved

to displace said roller and said gearing to permit convenient removal of said carrier, a lever connected with said member, a rotatable disk having a member adapted to engage and move said lever and adapted to permit restoration thereof, to its initial position after a cycle of movement, and transmission gearing in train between said disk and the Geneva movement and adapted at the conclusion of a cycle of movement of said disk to restore the Geneva movement to its original position therein.

7. In an automatic radio tuner, the combination of a condenser including a movable element adapted to establish selective tuning with the members of a group of stations operating on different wave lengths, a power transmission connection with said movable condenser element

adapted to be variably rotated and power actuated means for variably rotating the same, a clutch in said transmission connection including a manually retractable pin on the power actuated side of said clutch and a disk having a cam face affording a throated entrance to a notch adapted to receive the pin when the parts are clutched, and manually operated means for rotating the condenser when the transmission connection is unclutched and for rotating the cam faced disk therewith, the engaging of the clutch elements serving to cam the disk to position to receive the pin and restore the condenser element to a position corresponding with that occupied by the pin.

JOSEPH L. SWALLOW.
